UNITED STATES PATENT OFFICE.

CLARENCE HOWARD, OF HUTCHINSON, KANSAS.

BURIAL VAULT.

Application filed June 7, 1921. Serial No. 475,815.

To all whom it may concern:

Be it known that I, CLARENCE HOWARD, a citizen of the United States, and a resident of Hutchinson, in the county of Reno and 5 State of Kansas, have invented a new and useful Burial Vault, of which the following is a specification.

My invention relates to burial vaults and has as its principal object the provision of 10 a reinforced cement or other composition vault for enclosing caskets.

A further object of the invention is to provide a concrete or other composition vault which is waterproof and will preserve 15 the casket and its contents and which cannot be readily opened for the purpose of tampering with the contents thereof.

Still another object of the invention is to provide a vault of this character which embodies a novel reinforcing frame or skeleton and which is such as to facilitate the coating of the same with a plastic composition to complete the finished vault.

With the preceding and other objects and 25 advantages in mind, the invention consists in the novel combination of elements, construction and arrangement of parts and operations to be hereinafter more fully described, claimed and illustrated in the accompanying drawings, wherein:

Figure 1 is a top plan view of the vault having parts broken away;

Figure 2 is a vertical sectional view taken on line 2—2 of Figure 1;

35 Figure 3 is a horizontal sectional view taken on line 3—3 of Figure 2;

Figure 4 is a vertical sectional view taken on line 4—4 of Figure 2; and

Figure 5 is a detail perspective of the 40 reinforcing frame.

Referring in detail to the drawings where-in similar characters of reference designate similar parts throughout the several views, the numeral 5 designates a rectangular reinforcing frame or skeleton and includes pairs of upper and lower side rails or angle irons 6 and end rails or angle irons 7. The side and end rails are connected at their juncture by vertical angle irons 8 and secured to 45 these angle irons 8 and the side and end rails 6 and 7 are reinforcing plates 9. Also connecting the side rails 6 are vertical braces 10 and angularly disposed braces 11.

Surrounding the frame or skeleton 5 is a 55 sheet of relatively heavy reticulated material 12 such as galvanized iron fabric. The

frame 5 is embedded in a relatively heavy body of concrete or other plastic material 13, the latter, at its upper edge, extending above the frame 5 and beveled inwardly, as 60 indicated at 14.

For cooperation with the frame 5 there is provided a cover 15 which includes a rectangular frame 16 to which is secured a sheet of reinforcing or reticulated material 65 17. Like the reticulated material 10, this reticulated material 17 is embedded in a relatively heavy block of cement or other plastic composition 18. Embedded in the bottom wall of the body 13 and the cover 70 15 is a plurality of reinforcing bars or elements 18' and 20 respectively.

As shown in Figures 2 and 4, the rectangular frame 16 of the cover 15 sets in the upper angle irons 6 and 7 and is sealed 75 therein by a plastic bond 19 between the beveled edges of the body 13 and the edges of the cover 15.

Embedded in the cover 15 is a plurality of longitudinally extending reinforcing rods 80 20 while a reinforcing rod 21 extends transversely through the cover at the center thereof. In order to lift the cover 15, handles 22 are provided which include lengths of rod 23 having their ends extended laterally in opposite directions and bent around the longitudinal rods 20, as indicated at 24.

It is to be understood that the form of my invention herein shown and described is to be taken as a preferred example of the same, 90 and that various changes in the shape, size and arrangement of parts may be resorted to without departing from the spirit of the invention or the scope of the subjoined claim.

Having thus described my invention, what I claim as new and desire to secure and protect by Letters Patent of the United States, is:

A vault comprising a rectangular frame 100 including upper and lower pairs of angle irons, braces connecting the angle irons, a reticulated sheet surrounding the frame, a plastic body surrounding the reticulated sheet; a cover including a rectangular 105 frame, a sheet of reticulated material stretched across the frame, a plastic body in which the last mentioned reticulated sheet is embedded, the frame resting in the upper angle irons, and a plastic bond securing the cover 110 to the edges of the first mentioned body.

CLARENCE HOWARD.
